UNITED STATES PATENT OFFICE.

MELVIN R. HALL, OF COLUMBUS, OHIO.

DESIGN FOR A FONT OF TYPE.

57,522.

Specification for Design.

Patented Apr. 12, 1921.

Application filed July 16, 1920. Serial No. 396,848. Term of patent 3½ years.

To all whom it may concern:

Be it known that I, MELVIN R. HALL, a citizen of the United States, residing at Columbus, in the county of Franklin and State of Ohio, have invented a new, original, and ornamental Design for a Font of Type, of which the following is a specification, reference being had to the accompanying drawing, forming part thereof.

The figure is a plan view of the type, showing my new design.

I claim:

The ornamental design for a font of type, as shown.

MELVIN R. HALL.

Witnesses:

W. S. McDOWELL,
M. A. STEPHENS.
